UNITED STATES PATENT OFFICE.

ISIDOR KITSEE, OF PHILADELPHIA, PENNSYLVANIA.

PRODUCING MULTICOLORED SCREENS FOR PHOTOGRAPHY.

Application filed January 17, 1919. Serial No. 271,709.

To all whom it may concern:

Be it known that I, ISIDOR KITSEE, a citizen of the United States, residing at Philadelphia, in the county of Philadelphia and 5 State of Pennsylvania, have invented certain new and useful Improvements in Producing Multicolored Screens for Photography, of which the following is a specification.

10 My invention relates to an improvement in multi-colored screens.

The object of my invention is to produce a multi-colored screen directly on the celluloid out of which the photographic blank—15 moving picture film for example—is produced.

It is well understood that so far nearly all attempts to produce multi-colored screens for photographic blanks and more specially 20 for moving picture films required as the first step the surfacing of the celluloid with a gelatine film, so that the different colors may be applied to the gelatine, as the application of the usual color solutions to the 25 celluloid met with great difficulties.

I have discovered, that it is possible to produce color solutions, affecting the celluloid in different degrees and yet repelling each other when applied to the celluloid, in 30 other words I have discovered that it is possible to apply: first, figurations of one color to the celluloid proper and then wash the whole surface of the celluloid indiscriminately with a solution of a second color 35 without interference between the two colors.

My invention may be practiced with a two-color three-color or four-color screen but I will here describe my invention as applied to a two- as well as a four-color 40 screen; it being understood that the colors selected as examples, may be replaced by other colors, but the medium or solution carrying the colors should be strictly adhered to.

45 In the accompanying drawing Figs. 1 to 3 inclusive are plan views representing the different steps in a two-color screen. Figs 4 to 6 inclusive are plan views representing the different steps in a four-color screen.

50 I will now describe the mode or method of procedure in obtaining the required result, and in doing so I will refer to the different numbers as indicating the different parts of these figures, and I will here describe this my invention as being applied to moving picture films. But I will point

out first the method and means of producing at least two different color solutions, each of them desirably affecting the celluloid proper, but yet, not injuriously affecting each other. 60 I have discovered, that if a dye soluble in alcohol is dissolved in an alcoholic solution containing a dissolved, but suitable rosin or resin, the so colored solution, when applied to the surface of celluloid adheres to the 65 same strongly enough for all purposes, and does not spread or run and gives in fact a clear figuration if applied with the aid of a roller or other printing device, or if applied with the aid of a brush and the inter-position 70 of a suitable pattern. Great care has to be taken in the selection of such resin on account of the great number of requirements requisite for this purpose, such for instance as pliability even when dry, transparency, solubility and the like, and I have found after a series of experiments that 75 hardly any other resin answers all purposes beside the resin known as balsam, but of this genre only such balsams should be used, as 80 give a very clear and uncolored solution with alcohol, the Peru or the Canada balsam is well adapted for this purpose. In my experiments I have in some instances, first dissolved the color in the alcohol and 85 then added the balsam allowing to stand till the balsam was entirely dissolved. In some instances I dissolved first the balsam then added the color.

The method and means of producing the 90 second solution is simply to dissolve the color in a liquid adapted to dissolve celluloid, in other words in a solvent of celluloid and I have found that acetone is well adapted for my purpose. To this colored 95 acetone I add a material not only capable of restraining action of the dissolving property of the acetone, but also as an added repelling medium towards the first color when about dry. As such medium, I have 100 found that formaldehyde is well suited. To produce therefore this second solution, I dissolve the proper color in acetone and add then formaldehyde in diluted state. Both liquids give clear imprints on the celluloid, 105 but whereas the second solution impregnates the celluloid to a greater or less extent, the first only colors and adheres to the surface of the celluloid, and I call the first solution the "B-solution" and the second 110 the "C-solution." Wherever therefore in this application or claims following this ap-

2
plication I refer to the "B-solution," I understand under this expression, the solution containing the dissolved resin and wherever I refer to the "C-solution" I understand the solution containing the solvent of celluloid.

In Fig. 1, 1 indicates part of a moving picture film, 1^a the perforations with which the films are usually provided. In Fig. 2, 10 the configurations of one color here green, are indicated by the numeral 2. These configurations are here represented by dots, but their diameter is greatly exaggerated so as to clearly bring out their coloration. These 15 dots may be applied to the film with the aid of suitable printing devices or may simply be sprayed on with the aid of sprayers or so called nebulizers. For these configurations I use the "B-solution," and after drying 20 the configurations, I cover the free spaces between these configurations with the second color, here red, as is clearly indicated by the numeral 3 in Fig. 3. In reality these 25 spaces occupy a far smaller area, but it is necessary for me to exaggerate these spaces so as to clearly illustrate the coloration of same. This second coloration is produced with the aid of the "C-solution" and can be applied to the film, by simply going over 30 the surface of the film with the aid of a sponge or other suitable contrivance dipped in this solution, for the reason that this solution will not injuriously affect the first configurations. The film is then washed so as 35 to remove the surplus dye. When completed, the film will represent here the two colors green and red in required sequence.

I will now describe the production of the screen as illustrated in Figs. 4 to 6.

40 In Fig. 4, the part of the film is indicated by 1, its perforations by 1^a, and the longitudinal lines here representing the color red, by the numeral 4. These lines are produced with the aid of the "B-solution" and may be applied to the film with 45 the aid of rollers or other suitable printing devices.

In Fig. 5, which illustrates the addition of lateral lines, 5 indicates these lateral 50 lines, here blue. These lines produced with the "B-solution" may also be applied with the aid of rollers or other suitable printing

devices. Fig. 5, clearly illustrates these lines and the spaces between these lines. It has to be stated, that the lateral lines as 55 well as the longitudinal lines are spaced one from the other in a manner so that the spaces between each of the lateral lines as well as the spaces between each of the longitudinal lines occupy an area about equal 60 to the width of the lines themselves. All these lines together will therefore represent a net-work of lines, comprising here the two colors red and blue. But as the blue lateral lines cross the red longitudinal lines, the 65 junction, comprising the two colors red and blue will represent the additional color, blue-violet, if the blue predominates or red-violet if the red predominates, and this additional color is here indicated by the numeral 70 6.

After drying, the whole film is gone over, with the aid of a sponge or other suitable device, provided with the necessary color, here green, whereby the free spaces between 75 the lines are impregnated with the green color. This color is produced with the "C-solution" and will therefore not interfere with the coloration of the longitudinal or lateral lines. In Fig. 6, which represents 80 the finished screen the coloration of the, formerly free or blank spaces between the lines are indicated by the numeral 7.

It is obvious, that the colors enumerated 85 may be supplanted by other required colors.

It is also obvious, that the surplus color of the "C-solution" should be washed away.

Having now described my invention, what I claim as new and desire to secure by Letters Patent is:—

90 The method of producing a multi-colored screen integral with a celluloid moving picture film which consists in applying to said film directly at least two different dye-solutions, the first of said solutions having a dissolving action on the celluloid of said film and the second of said solutions adhering only to the surface of said celluloid.

95 In testimony whereof I affix my signature in the presence of two witnesses.

ISIDOR KITSEE.
